WILLIAM J. SMITH,

D. Anthony Usina
His Attorney.

UNITED STATES PATENT OFFICE.

WILLIAM J. SMITH, OF CLEVELAND, OHIO, ASSIGNEE TO THE AMERICAN STEEL AND WIRE COMPANY OF NEW JERSEY, A CORPORATION OF NEW JERSEY.

REEL.

Application filed December 2, 1924. Serial No. 753,456.

To all whom it may concern:

Be it known that I, WILLIAM J. SMITH, a citizen of the United States, and resident of Cleveland, in the county of Cuyahoga and State of Ohio, have invented certain new and useful Improvements in Reels, of which the following is a specification.

This invention relates to reels, and more particularly to reels for feeding or delivering wire or similar material to stapling machines, binding machines, or the like.

One object of this invention is to provide a reel of such construction that the flanges will have a maximum strength and will be free of any sharp corners or projections which might injure the hands of the operator when in use.

Another object is to provide a reel of this class having circular recesses in the inner faces of the flanges to receive the ends of the hollow core upon which the coil wire is formed.

A further object is to provide a reel of this class in which one flange is removable to permit the loading and unloading of coils of wire on the reel, and which flange is locked in position by a single nut.

A still further object is to provide a reel having the novel construction, design and combination of parts hereinafter described and illustrated in the accompanying drawings.

In the drawings,

Figure 1 is an end elevation of a reel constructed in accordance with my invention, having a portion of one flange broken away for clearness.

Figure 2 is a sectional plan thereof.

Figure 3 is a plan, partly broken away for clearness.

Figure 4 is a perspective of a roll of the wire adapted to be mounted on my reel.

Referring more particularly to the drawings, my improved reel, which is formed from aluminum or the like for the sake of lightness, comprises a supporting hub 2 having a centrally arranged bearing aperture 3 therein, so that it may be mounted on an axle or spindle of a machine, and having an integral flange 4 of considerably greater diameter formed on its one end. The hub 2 is cored out to form an aperture or recess

5 which lightens the hub structure. The end of the hub 2 opposite the flange 4 is reduced, forming a bearing portion 6 and a shoulder 6^a, and a second removable flange 7 having an aperture 7^a therein, is adapted to fit snugly around the bearing portion 6 and bear against the shoulder 6^a. A dowel pin 8 is secured in the shoulder 6^a and extends through a suitable aperture in the flange 7 to hold it against rotation and to center said flange.

The hub 2 is further reduced beyond the portion 6 and screw threaded as at 10 to receive a nut 11 having an enlarged flat face adapted to engage and hold the flange 7 in position.

The flanges are each provided with circular recesses 12 in their inner faces to receive the ends of the hollow core members 13 of the preformed coils of wire 14 adapted to be mounted on the reel.

The flanges 4 and 7 are further provided with radially disposed closed end slots or openings 15 and the hub 2 is provided with longitudinal grooves or slots 16 on a line with the slots 15. The lower ends of the slots or openings 15 are in alignment with the bottom of the grooves or slots 16, so as to permit free passage of a binding wire used in tying or binding the coils of wire before they are removed from the reel.

Heretofore when reels of this class were provided with slots or openings in the flanges, the slots or openings opened through the edge of the flanges, thus dividing the flanges into segments and greatly weakening the flanges and also being the source of considerable trouble in that the wire being uncoiled from the reel would become caught in the openings and break, and the open ends of said slots also were hard on the operator's hands.

With the present type of closed ended slots or openings all of the above difficulties are overcome.

Flanges 4 and 7 are provided with small apertures 18 adjacent their edges, through which the loose end of a coil of wire is adapted to be forced to temporarily hold it until the coil can be properly bound.

The nut 11 has a serrated peripheral face or surface and is also provided with suitable

depressions or apertures 21 to receive a suitable wrench or tool for operating it.

In Figure 4 I have shown a perspective view of the coils of wire 14 adapted to be used with this improved reel. These coils are wrapped on a tubular filler or core 13 of pasteboard or the like, which are of such size as to fit snugly on the hub 2 and are secured by binding wires 22. The core 13 is adapted to be used only once and to be destroyed when the wire is removed therefrom, thus eliminating the expense and trouble encountered in storing and returning the wooden reels and cores commonly in use.

15 My improved form of reel may be used either for forming or dispensing coils of wire. If used for forming coils, a filler 13 is placed on the hub 2, flange 7 is placed in position on the bearing portion 6 and nut 11 is screwed home to lock said flange in position. The wire is then wrapped on the filler to form a coil of suitable dimensions. After sufficient wire is wrapped, the free end of the wire is inserted in the apertures 18 in the flange 4 to hold it from unwrapping, and binder wires 22 are then passed through the slots or openings 15 and grooves 16 and lapped over the coiled wire and secured to hold the coil. The nut 11 is then removed and flange 7 and the coil of wire removed from the hub 2.

If used as a dispensing reel, a coil of wire suitably bound, as shown in Figure 4, is mounted on the hub 2. The flange 7 is placed in position and locked by the nut 11. The binding wires are then cut and the coil used. If desired to change the wire on the reel before it is all used, suitable binding wires 22 are passed through the slots or openings 15 and grooves 16 and lapped over the coil and secured to hold the unused portion of the coil from unwrapping. The nut 11 is then removed to permit the removal of the flange 7 and unused portion of the coil.

45 While I have shown and described only one particular embodiment of my invention it will be expressly understood that I do not wish to be limited thereto since various modifications may be made without departing 50 from the scope of my invention as defined in the appended claims.

I claim—

1. A reel for wire or the like comprising a hub, said hub having a bearing aperture 55 for mounting the reel on a shaft for rotation and also being provided with a recess entering from one end thereof to lighten said hub, said hub being further provided with a plurality of longitudinal grooves on 60 the periphery thereof, flanges on said hub, having radially disposed elongated closed ended openings registering with the grooves in said hub, said openings permitting said flanges to have a continuous smooth periphery and strengthening said flanges, said

flanges being spaced apart to hold a pre-formed coil of wire therebetween, said wire being formed on a hollow core, and each of said flanges having their inside faces provided with circular recesses to receive the ends of said core, one of said flanges being fixed to said hub, the other of said flanges having a centrally arranged aperture therein and being removably fitted over a portion of said hub, and a nut threaded on one end of said hub and bearing against said last named flange to hold it in operative position.

2. A reel for wire or the like comprising a hub, said hub having provisions for mounting the reel for rotation, and having a plurality of longitudinal grooves on the periphery thereof, flanges on said hub having radially disposed elongated closed ended openings registering with the grooves in said hub, said openings permitting said flanges to have a continuous smooth periphery and strengthening said flanges, said flanges being spaced apart to hold a preformed coil of wire therebetween, said wire being formed on a hollow core, and each of said flanges having their inside faces provided with circular recesses to receive the ends of said core, one of said flanges being fixed to said hub, the other of said flanges having a centrally arranged aperture therein and being removably fitted over a portion of said hub, and a nut threaded on one end of said hub and bearing against said last named flange to hold it in operative position.

3. A reel for wire or the like comprising a hub, said hub having provisions for mounting the reel for rotation, and having a plurality of longitudinal grooves on the periphery thereof, flanges on said hub having radially disposed elongated closed ended openings registering with the grooves in said hub, said openings permitting said flanges to have a continuous periphery and strengthening said flanges, said flanges being spaced apart to hold a preformed coil of wire therebetween, one of said flanges being fixed to said hub, the other of said flanges having a centrally arranged aperture therein and being removably fitted over a portion of said hub, and a nut threaded on one end of said hub and bearing against said last named flange to hold it in operative position.

4. A reel for wire or the like comprising a hub, said hub having a bearing aperture 120 for mounting the reel on a shaft for rotation and also being provided with a recess entering from one end thereof to lighten said hub, said hub being further provided with a plurality of longitudinal grooves on the periphery thereof, flanges on said hub having radially disposed elongated closed ended openings registering with the grooves in said hub, said openings permitting said flanges to have a continuous smooth periphery and 125

strengthening said flanges, said flanges being spaced apart to hold a preformed coil of wire therebetween, one of said flanges being fixed to said hub, and the other of said flanges having a centrally arranged aperture therein and being removably fitted over a portion of said hub, and a nut threaded on

one end of said hub and bearing against said last named flange to hold it in operative position.

In testimony whereof, I have hereunto signed my name.

WILLIAM J. SMITH.
